(No Model.)

J. KURTIS.

STOVE PIPE SHELF.

No. 319,101.

Patented June 2, 1885.

UNITED STATES PATENT OFFICE.

JOSEPH KURTIS, OF SPRINGFIELD, OHIO.

STOVE-PIPE SHELF.

SPECIFICATION forming part of Letters Patent No. 319,101, dated June 2, 1885.

Application filed September 15, 1883. (No model.)

To all whom it may concern:

Be it known that I, JOSEPH KURTIS, a citizen of the United States, residing at Springfield, in the county of Clark and State of Ohio, 5 have invented certain new and useful Improvements in Stove-Pipe Shelves; and I do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

My invention relates to improvements in 15 stove-pipe shelves; and it consists in the construction, combination, and arrangement of the several parts, as will be hereinafter described and claimed.

In the drawings, Figure 1 is a plan view 20 showing the supporting-band, shanks, &c., with one shelf in position. Fig. 2 is a side view of the shelf, the band being broken away. Fig. 3 shows the socket enlarged, partly in 25 vertical section, with the shelf-shank in position. Fig. 4 is a side view, and Fig. 5 a plan view of the shank and a portion of the shelf. Fig. 6 is a bottom plan view of the socket. Fig. 7 shows the clothes-drier rod. Fig. 8 is a side view of the outer end of the socket; 30 and Fig. 9 is a detail view showing a modified form of socket and shank, as will be described.

The supporting-band is composed of sections A A, hinged at a , and provided at their opposite ends with a suitable connecting-bolt, a' . 35 The sockets B are extended radially from this band, and are constructed with the top plate, b , and the side walls, b' , depending from the opposite sides of said top plate. At the base of the socket and near its lower end I form the 40 shoulder or seat b^2 , for the purpose presently described. The cross-bar b^3 is extended between the side walls, b' , at a point near their inner ends, and at or close to their lower sides, as clearly shown in Fig. 3. In the outer ends 45 of the side walls and from the upper sides thereof I cut slots b^4 . These slots are inclined downward, and are tapered from their upper to their lower ends, terminating in a point, as clearly shown in Figs. 2 and 3. The shelf C 50 is provided with shank C', extended from the shelf and inclined or bent downward, as shown.

This shank is provided at its outer end with a seat or shoulder, c , arranged to engage the shoulder b^2 of the socket, and a hook, c' , is formed on the under side of the shank near its 55 outer end, in position to engage the cross-bar b^3 in the operation of the invention. Lugs c^2 are projected laterally from the shank at the juncture of the latter and the shelf. These lugs are inclined and tapered to fit in the slots 60 b^4 cut in the socket.

In the operation of the device the band is secured to the stove-pipe and the shelf-shank is inserted in the sockets and rests in the position shown in Figs. 2 and 3. When the shelf 65 is not in use, it is moved upward and outward, as indicated in dotted lines, Fig. 2, until the lugs c^2 escape the slots b^4 , when it is turned down, the hook c' catching on cross-bar b^3 , as indicated in dotted lines, Fig. 2, and the shelf 70 is suspended in a vertical position. To place the shelf in a horizontal position the operation is about the reverse of the one before described. It will be seen that by forming the end slots inclined it is necessary to effect a displacement 75 of the shelf, that it be moved upward and outward, and the chances of its being jolted or jarred out of place are consequently reduced. By forming the slots tapering, as before described, and the lugs of a corresponding form, 80 the insertion of the latter is facilitated, and they are guided into place easier and with greater certainty, as will be understood. It is for this reason I prefer to taper the slots and lugs. It will be understood, however, that 85 where so desired the slots and lugs may be made with their sides parallel. It will also be understood that where so desired the socket, instead of having the slots formed in its side walls, might be constructed with its outer end solid 90 and the slot formed therein. In such case instead of constructing the lugs separate and projecting them laterally a single lug would be employed, which would be supported on a curved or arched rod projected from the upper 95 side of the shank, as shown in Fig. 9, or in other suitable manner, as desired. This, it will be appreciated, would be no departure from the principle of my invention, but would be simply a modification of form.

I prefer to construct the seat b^2 with a central notch, b^5 , in which fits the projection c^3 ,

formed on the upper side of shoulder or extension *c*. This construction prevents any lateral movement of the inner end of the shank, and the shelf is consequently held more firmly to its place.

In Fig. 7 I have shown the shank provided with a socket, *D*, to receive the stem *D'*, on which the kitchen-cloths or small articles of clothing may be hung to dry. The inner end 10 of the shank, it will be seen, is cut away, and the portion *D*² remaining is rounded to conform to the upper wall, *b*, against which it bears, as shown. It will be understood that all the shanks might be cut away in this manner on 15 their inner ends; but for the reasons stated I prefer the construction as shown, and before described.

Heretofore I have been granted a patent, No. 277,294, for a stove-pipeshelf, and a patent, No. 20 227,733, has been granted to one Coburn for a similar invention. I do not broadly claim any 25 of the constructions shown in said patents, but only the novel features of my present shelf. In my former patent the shelf is held by means of lateral studs on its shank fitting into grooves in the socket and supports rested on top of the socket. In the Coburn patent the shelf is held by its shank being inserted through an opening 30 in the outer end of the socket and bearing on the under wall of said opening and at its inner end under the supporting-band.

The invention sought to be covered by my present application is the result of long experience in the manufacture of stove-pipe shelves,

and seeks to provide simple constructions by 35 which the shelf will be securely held. This I accomplish by the form of the notches *b*⁴, and the corresponding formation of the lugs fitting thereinto, as described.

Having thus described my invention, what I 40 claim, and desire to secure by Letters Patent, is—

1. The improved means for supporting a stove-pipe shelf, consisting of a shelf-holding arm, *B*, provided in its outer end with *V*- 45 shaped retaining notch or notches *b*⁴, extended inward and downward at an angle, and the shelf-shank *C'*, having its outer portion or extremity engaged under a suitable stop or bearing, and having near its end next the shelf *V*- 50 shaped lug or lugs inclined outward and downward, and conformed to and adapted to drop into the *V*-shaped notch or notches *b*⁴, substantially as set forth.

2. The stove-pipe shelf composed of the 55 socket having top plate, and depending side walls provided in their outer ends with inclined notches, the cross-rod connecting the side walls, and the shelf-shank provided with a suitable hook, and having lateral inclined 60 lugs, all arranged and operating substantially as specified.

In testimony whereof I affix my signature in presence of two witnesses.

JOSEPH KURTIS.
